COT STRUCTURE

William Walger, Chicago, Ill.

Application May 3, 1937, Serial No. 140,372

4 Claims.

(Cl. 5—3)

This invention relates to cot structures and the like, and includes among its important objects the provision of a cot which may be folded up when not in use, and which may be otherwise folded so as to provide a table support.

Another important object is the provision of an innerspring structure which is simple and rugged and which affords increased comfort to the user.

A further object is a cot structure comprising a central frame section having depth, and having short end sections hinged thereto at each of its ends, together with especial hinge devices adapted to hold the end sections in raised position to receive and support a table member.

Yet another object is the provision of a device of the class characterized above, in which the central frame section has a fabric bottom upon which is disposed a spring assembly, which in turn is covered by a fabric top, while a fabric cradle or full-length cover is laid over the entire upper cot frame, thus providing reinforced load support and a novel housing for the springs.

Other objects and novel aspects of the invention will appear as the following description develops in view of the drawings, in which:

Fig. 1 is a side elevation of the cot structure in folded condition;

Fig. 2 is a side elevation of the cot unfolded or erected;

Fig. 3 is a top plan view of the erected cot with a portion of the cover fabric folded back;

Fig. 4 is an enlarged fragmentary vertical section viewed along line 4—4 of Fig. 3;

Fig. 5 is an enlarged fragmentary vertical section through the frame and springs and is taken along line 5—5 of Fig. 3;

Fig. 6 is an enlarged elevational detail of an end hinge and is taken along line 6—6 of Fig. 5;

Fig. 7 is a front elevation, partly in section, of the hinge of Fig. 6 and is viewed in the latter along line 7—7; while

Fig. 8 is a vertical median section of the erected cot arranged as a table.

A preferred form of the invention includes a frame 10 of elongated rectangular form and comprised, as seen in Fig. 3, of a pair of lateral frame rails 11 and a pair of longitudinal frame rails 12, all of oblong and preferably rectangular cross-section, arranged end to end with their lateral or side edge portions 13 of each rail disposed in parallel planes (Fig. 5), thus giving a maximum of depth to the frame, for reasons which will herein-after appear.

Each of the longitudinal side rails 12 has a movable section 12' attached to the ends thereof

by means of special end hinges 14. These hinges are in the form of a pair of triangularly shaped plates 14 having a plurality of mounting holes 15 (Fig. 6) adjacent the several corners thereof, and each having a pair of apertured ears 16 adjacent the base angles or corners opposite its apex.

Hinge plates 14 are mounted on their respective frame members 12 and 12' with their ears 16 in overlying relation, there being a pintle or rivet 17 extended through one pair of ears on opposite plates, and in this way, the section 12' may be pivoted relative to the section 12 from the folded condition seen in Fig. 1 to the extended condition seen in Fig. 2, there being, of course, a pair of hinges 14 at each end of the intermediate rails 12.

Referring again to Figs. 6 and 7, it will be observed that one of the hinge plates 14 is provided with a holding rod or arm 18 having one end portion bent into a lateral stud 19 pivotally seated in the opening of one of the ears 16 by having its free end peened or flattened therein. The opposite end of the holding rod 18 is bent to form a lateral projection 20 which is receivable in the opening of the ear 16' of the opposite plate when the sections 12' are in the position seen in Figs. 6 and 8, in which the arms 18 firmly hold the sections for the purpose of supporting a table section or top 20.

Each of the endwise or lateral frame members 11 is provided with an edge strip 21 which extends laterally outward of the member from its narrow side, and when the end sections 12' are folded up into the position seen in Fig. 8, the top 20 may be securely lodged in the ledge formation provided by these opposite edge strips, while the several holding arms 18 on the hinges assure adequate support for any reasonable load applied to the table.

Suitable leg members 23 are pivotally connected to the main frame 12 as at 24, and desirably may be arranged in pairs with the legs of each pair being connected together by stop rods 25 attached to each leg at such a distance from the pivotal points 24 that when the legs are extended, as in Fig. 2 for example, these stop rods will bear firmly against the underside of the frame, thus limiting the outward or extending movement of the legs and giving greatly increased structural support to the frame. The pairs of legs are also desirably provided with tie rods 26, which, in cooperation with the stop rods, provide a very firm cot structure. The particular leg structure briefly outlined above, is described and claimed in my co-pending application, Serial No. 140,370, filed May 55

3, 1937, to which attention is directed for further details.

A novel "innerspring" arrangement is also provided in the present invention in the form of a bottom fabric or canvas covering 28 having its marginal edge portions folded under and stapled to the bottom narrow edge portions of the central or main frame 12, as at 29 (Figs. 4 and 5) near each of its ends the central frame section 12 has a long thin strip 30 of fibre or metal of the same width as the frame rail and extended laterally across the frame for attachment to the central part of the same by any suitable means such as the nails 31. In this manner, the main longitudinal side rails 13, the end strip 30, and the fabric bottom 28 provide a well in which is disposed a set of coil springs 32, over the top of which is laid a padding 33 (Figs. 3, 4, 5).

After the springs 32 are arranged on the bottom 28, a protective closing sheet or strip 34 is stapled as at 35 onto the upper horizontal edge portion of the central frame 12, thus closing off the entire spring assembly.

Over the protective sheet or cover 34 is then laid a full length cradle fabric 36 of canvas or the like, and this fabric is stapled down all along the top horizontal edge surface of the whole frame, including the main frame portion 12 and the two hinged end sections 12', as indicated at 37.

It will thus appear that when the load of an occupant is applied to the cot in its fully extended condition (Fig. 2), that this load will be distributed in part over the top cradle fabric 36, somewhat in the manner of the ordinary cot, and much of this part of the load will be divided between the middle and two end sections. In addition, an appreciable part of the load will be transmitted to the protective cover sheet 34 in the central region of the cot where the load is concentrated, while still another considerable portion of the load is sustained by the spring assembly 32, yieldingly supported on the bottom canvas or fabric 28.

Thus, the several objects of the invention are accomplished in a simple and economical fashion, and the resulting cot structure, in addition to being rigid, very strong and durable, is considerably more comfortable than other forms of cot.

An additional feature of the invention resides in the arrangement of the hinges 14 and the position of the pintles 17 thereof a distance above the top edge of the side rails 12 such that when the movable end sections are folded back upon the main section in the manner shown in Fig. 1, a space indicated at 40 remains between the confronting edges of the folding end sections 12' and the top edges of the middle rails 12, which is adequate to receive the table top member 20 and hold the same in place for transportation with the cot structure in its folded condition. In the latter condition the board is prevented from sliding out of its seat in a lateral direction by 65 the protruding portions 16 of the hinge members.

The preferred form of structure set forth herein for illustrative purposes may be variously re-arranged and changed without departing materially from the spirit of the invention, and it is

understood that the appended claims are to include all said modifications and changes and all equivalent expedients for accomplishing the structure disclosed.

Having thus described my invention, what I claim as new and desire to protect by Letters Patent is:

1. A cot including a central frame section and end sections attached by means of hinges to opposite ends of said central section and adapted to fold back onto the latter, means co-operable with said hinges for holding said end sections in a substantially upright position relative to said central section, a removable table section adapted to fit between said central section and said end sections when the latter are folded onto the former, and means on said end sections and co-operable with the latter to receive and support said table section in position on the end sections in their aforesaid upright position. 20

2. A cot including a central frame section having a folding leg structure and movable end sections attached by means of hinges at opposite ends of said central section, means co-operable with said hinges to hold said end sections in a 25 determined raised position to support a table section, a removable table section, and means on said end sections to receive and retain said table section in place when said end sections are in raised position. 30

3. A cot including a main frame section and movable end sections at its opposite ends, together with a flexible cradle member extended over and attached to said main and end sections, the latter being pivotally attached to the main section by means of hinges constructed to permit the folding of the end sections back onto the main section in spaced relation to the latter, such that a substantially planar table member may be held between said main section and said 40 folded-back end section, means arranged with said hinges for holding the same in a predetermined position to position said end sections in substantially upright relation to said main section, a substantially planar table member receivable on the upper ends of said end sections in their raised position as aforesaid, means on said end sections preventing dislodgement of said table member, the latter member being received between said main section and said end sections 50 when the latter are folded back in the manner aforesaid.

4. A combination cot and table including a main frame section with movable opposite end sections adapted to fold back onto the main section, hinge means connecting said end and main sections for the purpose aforesaid, means forming part of said hinge means and adjustable to position said end sections in substantially raised position relative to said main section, said hinge means being adapted to provide a space between said end and main sections when folded back as aforesaid, a removable table member adapted to fit into and be held in said space between the end and main sections, the outermost free lateral edge portions of said end sections being provided with a flange forming a ledge into which said table member may be fitted when said end sections are in raised position to form a table. 60
